**STAND FOR AN ELECTRICALLY-
POWERED ERASER OR THE LIKE**

Francesco Collura, New York, N.Y., assignor to Keuffel
& Esser Company, Morristown, N.J.

Filed Dec. 22, 1970, Ser. No. 26,615

Term of patent 14 years

Int. Cl. D19—02
U.S. Cl. D74—5

FIG. 1

FIG. 2

FIG. 3

FIG. 4

FIG. 5

FIG. 1 is a top plan view of a stand for an electrically-powered eraser or the like embodying my new design;

FIG. 2 is a rear elevational view thereof;

FIG. 3 is a right-side elevational view, the left side being a mirror image thereof;

FIG. 4 is a front elevational view thereof; and

FIG. 5 is a bottom plan view thereof.

I claim:

The ornamental design for a stand for an electrically-powered eraser or the like, as shown and described.
